(57) **CLAIM**

The ornamental design for a medical device housing, as shown and described.

DESCRIPTION

FIG. 1 is a top, front, right side perspective view of a medical device housing according to a first embodiment of our new design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof;

FIG. 7 is a bottom plan view thereof;

FIG. 8 is a top, front, right side perspective view of a second embodiment thereof;

FIG. 9 is a front elevation view of FIG. 8;

FIG. 10 is a rear elevation view of FIG. 8;

FIG. 11 is a right side elevation view of FIG. 8;

FIG. 12 is a left side elevation view of FIG. 8;

FIG. 13 is a top plan view of FIG. 8; and,

FIG. 14 is a bottom plan view of FIG. 8.

The dot-dash broken lines represent boundaries of the claimed design and form no part thereof. All other broken lines illustrate portions of the medical device housing that form no part of the claimed design.

1 Claim, 14 Drawing Sheets
